INVENTOR

Theodore Romaine
BY
Ferd P. Fischer
ATTORNEY

UNITED STATES PATENT OFFICE.

THEODORE ROMAINE, OF IRVINGTON, NEW JERSEY.

DENTAL MIXING SLAB.

Application filed May 2, 1924. Serial No. 710,577.

To all whom it may concern:

Be it known that I, THEODORE ROMAINE, a citizen of the United States, residing at Irvington, in the county of Essex and State 5 of New Jersey, have invented certain new and useful Improvements in Dental Mixing Slabs, of which the following is a specification.

This invention relates to slabs, as used by 10 dentists and others in mixing materials, in limited quantities, for preparing plastic cements or like bite-taking compounds that have quick setting properties and harden very rapidly.

Such cements required quick and dexterous handling and frequently pass the stage 15 of proper plasticity before they can be applied, thus necessitating the employment of more than one slab in performing an operation extending over any appreciably unusual period of time.

As such cement is strongly adherent to the slab upon which it is mixed, it is not usually possible to delay the operation for the purpose 20 of cleansing the slab, preparatory to mixing a fresh quantity of the material, thus increasing the advantages of having several of the slabs ready for use.

It is therefore one of the objects of the 25 invention to provide a plurality of relatively thin slabs within a container capable of being used as a support and forming a convenient adjunct to an office or laboratory in which it will be used.

Another purpose is to produce a device in 30 which the slabs are securely held from lateral or longitudinal movement at all times, but which may be instantly raised to present the adjacent underlying slab in position and 35 condition for service.

A further aim is in the provision of a plurality of duplicate slabs, uniform in size and thickness, each having level upper and 40 lower surfaces without irregularities that tend to obstruct the mixing operation or subsequent cleaning.

These several aims and objects are accomplished by the simple and novel construction and arrangement of parts hereinafter described and shown in the accompanying drawing, constituting a material part of this disclosure, and in which:—

Fig. 1 is a perspective view showing an embodiment of the invention in normal, 55 fully assembled position.

Figure 2 is a transverse sectional view of the same, the upper slab being raised above the top of the container body.

As shown in the drawing, the invention includes an oblong rectangular body 5 preferably of considerable weight, the same resting on pads 6 disposed near the corners, these pads or feet acting as cushions to avoid marring contacting surfaces and also tending to prevent slipping or displacement of 60 the apparatus.

At each upper corner, extending uniformly from the adjacent end and side surfaces, are thin plate-like outstanding projections 7, their curved upper edges being raised at 70 the centers to a uniform height as at 8 and having their flat inner surfaces disposed in the planes of the outer surfaces of the body, constituting in effect the corner elements of 75 a frame enclosing the structure.

In order to conveniently raise the apparatus, finger engaging recesses 9 are disposed lengthwise centrally in the side surfaces of the body 5.

The upper surface 10 of the body is 80 smooth and level throughout except for in-reaching finger recesses 11 in each side and by which the slabs 12 may be conveniently raised.

The slabs 12 which are essentially plates, 85 conform to the dimensions of the body 5 in length and width, are of uniform parallel thickness throughout and provided with rounded edges on all sides, these slabs neatly fitting within the corner elements 7 by which 90 they are positioned and held from sliding in any direction.

Any preferred number may be used within the limits of the containing corners 7, four being shown as constituting a set suitable 95 for ordinary purposes.

Due to their rounded edges the slabs may be readily picked up by the fingers of an operator, the lowermost slab being accessible by reason of the recesses 11. 100

As the slabs or plates 12 are straight and level the cementitious material may be mixed conveniently with a pallet knife or the like, and thereafter the surfaces scraped and effectively cleansed of all adherent matter by ordinary methods.

While any suitable material may be used for the slabs, glass is preferred and the same may be subjected to a considerable degree of heat, as in using gutta-percha, or 110

to moisture, as water in saturating and mixing oxy-phosphate, plaster of Paris and like other dry pulverent substances as used in the art.

From the foregoing it will be seen that a simple device for this purpose has been disclosed in the preferred form of its embodiment, but it is not desired to restrict the details to the exact construction shown, 10 it being obvious that changes, not involving the exercise of invention, may be made without conflicting with the scope of the appended claims.

Having thus described my invention, 15 what I claim as new and desire to secure by Letters Patent, is:—

1. A mixing slab comprising a thin oblong rectangular body, outstanding frame corners integral therewith and extending to 20 a uniform height thereabove, and a plurality of plates having rounded edges disposable within said corners on the upper surface of said body.

2. A mixing slab comprising a solid oblong rectangular body, parallel in thickness and of relative heavy weight, said body having cushion pads on its lower surface near the corners thereof, integral plate elements at each upper corner of said body 30 extending above the upper edges of the body, and a plurality of uniformly thick plates disposed in tiered relation on the upper surface of said body within the confines of said corner plate elements, said 35 body having finger recesses in its upper surface extending in from its side whereby said plates may be raised.

3. A mixing slab comprising a relatively

heavy rectangular base having finger receiving recesses in opposite sides and other recesses extending from the sides into its upper surface, a plurality of parallel plates uniform in size with said base, said plates being rounded on each edge, and co-operative means raised from the outer surfaces 45 of said base for causing registration of said plates with said base.

4. A mixing slab comprising a relatively heavy rectangular base having finger receiving recesses in opposite sides and other recesses extending from the sides into its upper surface, cushion pads on the lower surface of said base near the corners thereof, a plurality of uniformly thick plates 55 disposable on the upper surface of said base, said plates being equal in area to said upper surface and having rounded edges on all sides, and means formed on said base to cause registration of said plates when disposed thereon.

5. A mixing slab comprising a relatively heavy rectangular base having finger receiving recesses in opposite sides and other recesses extending from the sides into its upper surface, duplicate plates mounted in 65 tier formation on said base, said plates having rounded edges, and co-operative elements on said base for maintaining said plates in registration thereon, said plates being removable singly or collectively.

This specification signed and witnessed this first day of May, 1924.

THEODORE ROMAINE.
